UNITED STATES PATENT OFFICE.

GEORGE S. WITHAM, JR., OF HOOSICK FALLS, NEW YORK, ASSIGNOR, BY MESNE ASSIGNMENTS, TO INTERNATIONAL PAPER COMPANY, OF NEW YORK, N. Y., A CORPORATION OF NEW YORK.

METHOD AND APPARATUS FOR BARKING LOGS.

1,277,808.

Specification of Letters Patent.

Patented Sept. 3, 1918.

Application filed July 31, 1912. Serial No. 712,405.

To all whom it may concern:

Be it known that I, GEORGE S. WITHAM, Jr., a citizen of the United States, residing at Hoosick Falls, county of Rensselaer, State 5 of New York, have invented certain new and useful Improvements in Methods and Apparatus for Barking Logs; and I do hereby declare the following to be a full, clear, and exact description of the invention, 10 such as will enable others skilled in the art to which it appertains to make and use the same.

My present invention relates to a method and apparatus for removing the bark and 15 color from logs, and especially from those logs which are to be used in the manufacture of wood pulp for paper-making, the object being to remove the bark and color without removing any of the solid wood or splintering 20 the fiber of the outer surface of the solid wood.

The invention consists primarily in providing a method and means whereby the bark and color can be removed by one or 25 more jets of water having high velocity, the water being projected under pressures ranging anywhere from five hundred to three thousand pounds per square inch (and, preferably about 700 to 800 pounds per square 30 inch, for spruce wood and the like in the condition in which it usually arrives at the mill) in jets which are directed to lift and remove the bark from the solid logs; and secondarily, in providing means for first 35 bruising the bark to loosen it from the log and then suitably directing the water jets to remove the bark and the surface color. By the jets alone or when the bark is first bruised and the jets then applied, no waste 40 of the pulp fibre is occasioned.

Various methods of removing bark from logs have been suggested and attempted with varying degrees of success, among these being abrading and chipping devices and 45 numerous instances of the use of cutting knives. So far as I am aware, all methods so far advanced for machine rossing have sought to break up the bark in the course of its removal. I am also aware that water in 50 jets, usually at moderate pressure, has been employed to remove the fragments of bark after the bark as a whole has been disintegrated.

The herein described method of removing the bark differs essentially, however, from 55 all of the above mentioned ways and means in that a separation of the contiguous and adhering surfaces of the bark and log is first accomplished before any effort toward breaking up the bark is made, the breaking up of 60 the bark being merely an incident to its entire removal from the log. In fact the preservation of the continuity of the bark at or near the points where it is being separated from the surface of the log is a factor which 65 is, in a measure, responsible for the successful operation of this process.

Owing to the irregular form of a log, cutting means which completely remove the bark necessarily disfigure the surface of the 70 log and those cutting means which cut through the bark or separate it into sections of small area which sections are afterward removed by water jets or other means, cut through and splinter the surface of the log 75 which is an effect not to be desired when the log is to be used for paper making.

The result most desired to be obtained by a rossing machine is that it shall peel off the bark in relatively large pieces and remove 80 the intermediate skin between the bark and wood known as color leaving the surface of the solid wood clean and smooth. This I am enabled to accomplish with a jet of water under high pressure directed at an acute 85 angle, first, against the bark to make an opening therethrough, and then against the adhering surfaces of the bark and wood. In order to further facilitate the action of the water jet when the bark adheres tenaciously 90 as with some woods, I bring pressure to bear upon the bark through the medium of rolls which at the same time may present various portions of the surface of the log to the jet and bruise the bark without substantial destruction of its continuity, which bruising 95 serves to increase the diameter of the bark preparing it for subsequent removal by the water jet. I may corrugate the rolls which bruise the bark but in order to avoid any 100 destruction of the fiber of the wood by transverse cuts or dents, I design the corrugations to lie parallel to the grain or lay of the fiber of the wood.

I have illustrated in the accompanying 105 drawings several modifications of apparatus

for carrying the herein-described process into effect, Figures 1, 2 and 3 disclosing a preferred form which is capable of first bruising the bark and then removing it by the high pressure water jet or applying the jet without the bruising action upon the bark, while Figs. 4, 5, 6 and 7 show devices for applying the jet alone in effective ways.

In the drawings,
10 Fig. 1 is a side elevation partly in section of the first-named machine;

Fig. 2, a front elevation of the same, and
Fig. 3, a cross section on line 3—3 of
Fig. 2.

15 Fig. 4 shows an organization in which the logs are fed by abutting one against another end to end through a circular series of high pressure water jets which strip off the bark and cleanse the wood;

20 Fig. 5 is a section on line 5—5 of Fig. 4;

Fig. 6 shows an organization in which a series of logs are fed and rotated by a conveyer which presents all parts of the surface of the log to the action of fixed jets; 25 and

Fig. 7 is a cross-section on line 7—7 of Fig. 6.

Referring to the drawings, the machine illustrated in Figs. 1, 2 and 3 has an upright 30 frame A upon the front side of which vertical guideways B are provided. A horizontal chain conveyer C is located across the machine forward of the guideways B and will be accompanied by the supports and 35 guides (not shown) which are usually provided for such conveyers.

Two carriages D and E are mounted to slide vertically upon the guideways B. The lower carriage D of the two is secured to a 40 piston rod F connecting with a piston G working in an upright cylinder H at the bottom of the machine, the arrangement being devised to effect vertical movement of the carriage D upon the guideways B when 45 a motive fluid under pressure is caused to act upon one or the other side of the piston G in cylinder H.

The carriage D is provided with two rolls I mounted to rotate in bearings with their 50 axes substantially parallel to the conveyer chain C. The rolls I are mounted on opposite sides of the conveyer chain C and a space is left between their surfaces sufficient to admit of their passing the conveyer chain 55 C in their upward and downward movement with the carriage D. The shafts of the rolls I are provided with worm gears J which are driven by worms K on a horizontal shaft L.

60 The horizontal shaft L is provided with a pulley M driven by a belt N which is in turn driven from a pulley O, on a counter-shaft P. An idler pulley Q bears on the belt N and takes up the slack therein occasioned 65 by the lowering of the carriage D.

The upper carriage E is secured to a piston rod R connecting with a piston S working in an upright cylinder T at the top of the frame A and this arrangement is devised to effect vertical movement of this carriage when a motive fluid acts upon one or the other side of the piston S.

70 Two rolls U are mounted parallel in resilient bearings V upon the carriage E in similar positions to those occupied by the 75 rolls I upon carriage D, but the rolls U are not necessarily provided with driving means and no such means are shown.

75 A handle W operates a valve to admit the motive fluid to either the lower or the upper 80 side of the piston G to cause the carriage D to rise to the upper limit of movement of said piston or fall to its lower limit of movement while a valve X normally admits the motive fluid to the under side of piston 85 S and keeps the carriage E in its upper position until the carriage D has risen far enough to permit the rolls I to lift the log to be barked off the conveyer chain. The carriage D then strikes a rod x and pushes 90 it up during the completion of the upward movement of carriage D and the rod x reverses the valve X and causes a downward movement of the carriage E until the rolls U bear upon the log.

95 A vertical pipe Y is carried by the carriage D and has a sliding connection through a stuffing box y with a stationary vertical supply pipe y', and a cross pipe Z having a series of jet nozzles is mounted upon the 100 upper end of this pipe. The cross pipe Z extends the full width of the rolls I and is directed tangentially just above the surface of the outside roll at approximately that point on said roll where the log will 105 bear.

The operation of this machine is as follows: When a log carried by the conveyer-chain C reaches a position directly over the rolls I, the operator by means of the handle 110 W admits the motive fluid to the underside of the piston G which causes the carriage D to rise and lift the log above the carrier-chain C. As the rolls are continually revolved, the log will be turned over and over 115 upon them. As the carriage D approaches the upper limit of its movement, it contacts and lifts the rod x, which reverses the valve X and admits motive fluid to the upper side of the piston S causing the upper carriage 120 E to descend until the rolls U press upon the upper side of the log. The pressure of the four corrugated rolls upon the bark bruises it and loosens it from the body of the log. The operator now turns on the high-pressure 125 jet which quickly cuts through the bark and impinges tangentially upon the adhering surfaces of the bark and the log proper, continuing to so impinge as the log is rotated, stripping the bark off in a substantially con- 130

tinuous sheet. When the bark has been removed, the jet is allowed to remove any color which may still cling to the surface of the wood and is then shut off and the handle 5 W reversed, admitting the motive fluid to the upper side of the piston G causing the descent of the lower carriage D. The upper carriage E and the valve rod x follow during the commencement of downward movement 10 of the lower carriage until the valve rod x reverses the valve X; whereupon, the carriage E rises and the log is deposited by the further downward movement of the lower carriage D upon the carrier-chain to 15 be removed thereby making way for the following log.

In Figs. 4 and 5, I have illustrated a hollow pipe ring a which is placed in such relation to a series of conveyer rolls b that the 20 logs traveling upon said rolls will pass through this ring. The ring a is provided with a circular series of jet nozzles which direct the high pressure jets between the adhering surfaces of the bark and the log and strip the bark from the log in longitudinal 25 strips. When this form of device is used, I prefer to feed the logs through the ring by abutting the logs end to end and permitting the following log to push the one in 30 advance of it.

In Figs. 6 and 7, I have shown a conveyer consisting of side guides c and feed rolls d mounted at an angle to the guides to give the logs an advancing movement and at the 35 same time revolve them about their axes. When this type of conveyer is used, it is not necessary to provide a circular series of jets but a short series of jets impinging upon the top of the logs will operate in a spiral 40 path to strip the bark and effect substantially the same result as is obtained with the apparatus shown in Figs. 4 and 5.

It will be seen that the method involved in the present invention includes subjecting the bark to the action of a water-jet of such 45 high velocity as to disrupt and remove it, in contradistinction to preliminarily comminuting or chopping the bark into small fragments. So also, a characteristic feature of the invention consists in introducing the water-jet between the bark and the solid wood of the log and disrupting the bark by the action of the jet, which under-runs the bark and pries it up from the solid wood 50 of the log. Furthermore, the invention contemplates specifically breaking through the bark initially by the action of the high pressure water-jet, in a direction approximately tangential to the periphery of the solid wood of the log, that is to say, along 55 the line of normal cleavage of the outer periphery of the solid wood of the log and the inner periphery of the bark.

Having thus described my invention, what I claim is:

65 1. The method of barking logs which con-

sists in removing the bark by causing a water-jet of sufficiently high velocity to cut through the bark and to under-run and thereby separate the bark from the solid wood of the log; substantially as described. 70

2. The method of barking logs which consists in bruising the bark upon the log without destroying its continuity and removing the bruised bark by introducing a water jet of high velocity between the bruised bark 75 and the solid wood of the log; substantially as described.

3. The method of barking logs which consists in effecting an initial opening of the bark by a jet of water having a high velocity and subsequently removing the bark by the impingement of said jet tangentially at the continuous surfaces of the bark and log and thereby causing the water-jet to under-run and pry up the bark from the solid 85 wood of the log; substantially as described.

4. The method of barking logs which consists in subjecting the bark to the action of a water jet of sufficiently high velocity to disrupt and remove the bark from the log in 90 substantially its natural condition without previous treatment of the bark.

5. The method of barking logs which consists in first loosening the bark from the log by bruising the bark without destroying its 95 continuity and then effecting its entire removal by introducing a high velocity jet of water between the bruised bark and the solid wood of the log; substantially as described.

6. The method of barking logs which consists in first subjecting the log to rolling pressure to bruise and loosen the bark without destroying its continuity and then effecting the disruption and removal of the bark by the impingement of a jet of water 10 having a high velocity upon the adhering contiguous surfaces of the bark and log, whereby the water-jet is caused to under-run the bark and pry it from the log; substantially as described. 110

7. The method of barking logs which consists in causing a jet of water at a pressure within the range of 500 to 800 lbs. per square inch to cut through the bark and impinge tangentially upon the line of separation between the bark and log and thereby under-run the bark and pry it from the log; substantially as described. 115

8. The method of barking logs, which consists in disrupting the bark by a water-jet 120 of high velocity, and introducing the water-jet between the bark and the solid wood of the log to remove the bark by the action of the jet; substantially as described.

9. The method of barking logs, which consists in subjecting the bark to the action of a water-jet of such high velocity as to initially disrupt the bark and thereafter remove the same. 125

10. In a log barking machine, the combi- 130

nation of a log carrier, a vertically movable carriage, positively driven log supporting rolls mounted upon said carriage and arranged to receive and lift a log from said 5 carrier when said carriage is moved upwardly, and a jet nozzle designed to project a high velocity jet against the log adjacent its point of contact with one of said rolls and in a direction approximately tangential 10 to the surfaces of the log and roll; substantially as described.

11. In a machine for barking logs, the combination of a log carrier, a carriage movable transversely of said carrier to remove 15 logs therefrom, positively driven rolls on said carriage adapted to receive and rotate a log, and a jet nozzle mounted to move with said carriage and project a high velocity jet in a direction to impinge at an 20 angle upon the surface of a log resting upon said rolls; substantially as described.

12. In a machine for barking logs, the combination of a log carrier, a vertically movable carriage to remove logs therefrom, 25 a hydraulic piston and cylinder for operating said carriage, a second vertically movable carriage, a second hydraulic piston and cylinders for moving said second carriage, log gripping rods on said carriages, means 30 for driving one or more of said rolls, and a jet nozzle mounted on one of said carriages for projecting a high velocity jet against a log gripped by said rolls; substantially as described.

13. In a machine for barking logs, the combination of a log carrier, a vertically movable carriage, a hydraulic piston and cylinder for moving said carriage to lift a 35 log from said carrier, positively driven log supporting rolls mounted on said carriage, a jet nozzle mounted on said carriage and directed at an angle toward the point of support of a log on one of said rolls, a water supply pipe, a sliding joint between said 40 nozzle and said pipe, a driving shaft, and an extensible driving connection between said shaft and said rolls; substantially as described.

14. In a machine for barking logs, the 45 combination of a carrier, a log lifting and supporting carriage, a log retaining and pressing carriage, hydraulic pistons and cylinders for said carriages, and means actu-

ated by said log lifting and supporting carriage for controlling the movements of said 55 log retaining and pressing carriage; substantially as described.

15. In a machine for barking logs, the combination of a frame having vertical guideways, a carrier running transversely 60 of said guideways, hydraulically operated carriages mounted to move in said guideways, bruising rolls mounted upon said carriages, a power drive for the said rolls on one of said carriages, and a jet nozzle mounted on one of said carriages and directed to project a high velocity jet in proximity to the face of one of said rolls, and operating means for said carriages whereby a log may be lifted from said carrier, held and bruised 65 between said rolls and the bark incised and peeled off by said jet; substantially as described.

16. In a log barking machine, the combination of a log advancer, a log rotator, a 75 jet nozzle positioned to direct a jet of water against the rotating log at an angle to its surface, and means for supplying the water to said nozzle at a velocity sufficient to initially penetrate the bark and thereafter 80 strip it from the log.

17. In a log barking machine, the combination of an advancing log carrier, a carriage adapted to raise a log from said carrier, rolls on said carriage for rotating the 85 raised log, and a jet nozzle positioned to direct a high velocity water jet at an angle to the log and upon the contiguous surfaces of the log and bark, whereby the bark is stripped from the log by the force of the 90 water jet; substantially as described.

18. In a log barking machine, the combination of an advancing log carrier, a pair of roll carrying oppositely moving carriages adapted to lift a log from said carrier, and 95 roll it between said rolls, and a high velocity water jet arranged to impinge upon a log being rolled between said carriages; substantially as described.

In testimony whereof I affix my signature, 100⁰ in presence of two witnesses.
